United States Patent Office.

B. F. BEAN, OF SCHUYLKILL, PENNSYLVANIA.

Letters Patent No. 79,100, dated June 23, 1868.

IMPROVED IMPLEMENT.

The Schedule referred to in these Letters Patent and making part of the same.

TO ALL WHOM IT MAY CONCERN:

Be it known that I, B. F. BEAN, of Schuylkill, in the county of Chester, and State of Pennsylvania, have invented a Combined Tongs and Wrench; and I do hereby declare the following to be a full and exact description of the same, reference being had to the accompanying drawings, which are made part of this specification, and in which—

Figure 1 represents a side view, in perspective, of my invention.

My invention consists in combining in one instrument the mechanical implement called the tongs, and the common hand or monkey-wrench.

In order to effect this, I construct tongs, as shown in the accompanying drawing, having, at the point A, upon one of the arms or levers, B C, a projection, D, which serves as the fixed jaw of a wrench. The other jaw of the wrench is shown in the same drawing at E. This jaw may be movable, sliding upon the arm B C, and operated by the screw G and nut H, forming a monkey-wrench, or it may be a solid jaw projecting from the arm or lever B C, and forming, with the jaw D, a fixed wrench.

The jaws of the tongs are inclined at such an angle that, when closed, only the tips of the jaws come together, and when opened the jaws are capable of grasping nuts of different sizes.

The wrench may be made of any kind of material or metal.

Having thus described my invention, what I claim as new, and desire to secure by Letters Patent, is—

The combined implement herein described, consisting of the tongs B C and screw-wrench C D E, the movable jaw of the latter being made adjustable upon the arm or handle C by a nut, H, which is fitted to a screw-thread cut upon the arm C, the whole constructed and operating in the manner and for the purpose specified.

B. F. BEAN.
